UNITED STATES PATENT OFFICE

149,861

DESIGN FOR A STEREOPTICAN VIEWER

Burton Sparling Davis, Kingston, N. Y.

Application February 7, 1948, Serial No. 144,343

Term of patent 14 years

(Cl. D61—1)

To all whom it may concern:

Be it known that I, Burton Sparling Davis, a citizen of United States, residing at Kingston, in the county of Ulster and State of New York, have invented a new, original, and ornamental Design for a Stereoptican Viewer, of which the following is a specification, reference being had to the accompanying drawing, forming part thereof.

In the drawing:

Fig. 1 is a side elevational view of a stereoptican viewer showing my new design;

Fig. 2 is a front elevational view thereof.

I claim:

The ornamental design for a stereoptican viewer, substantially as shown.

BURTON SPARLING DAVIS.
